UNITED STATES PATENT OFFICE

GEORGE A. MILKIE, OF BROOKLYN, NEW YORK

TOBACCO PIPE

Application filed August 16, 1929. Serial No. 386,315.

This invention is directed to an improvement in tobacco pipes, wherein provision is made for cooling the smoke from the tobacco, for insuring against any tobacco particles or liquid reaching the mouth of the user, and for preventing any possibility of clogging in use.

The primary object of the invention is the production of a tobacco pipe in which the incoming air is drawn through the stem remote from the bowl, and compelled to travel lengthwise and in opposition to the passage of the smoke in a smoke duct, the incoming air thus serving to cool the duct and thereby 10 the smoke during the passage of the smoke to the mouth.

A further object is the provision of a receptacle serving as a condensate chamber, to which the smoke is initially delivered, this 20 chamber being open to the external influence of the incoming cool air, thus insuring precipitation of any liquid in the smoke and cooling the smoke through the walls of the chamber.

25 A further object of the invention is the provision of an indirect connection between the stem and bowl to thereby tend to prevent any liquid or tobacco particles from being delivered with the smoke.

30 A further object is to construct and relatively arrange the various parts of the pipe so that they are readily removable and replaceable when necessary for cleaning or repair, with the parts conveniently renewable 35 when desired.

The invention is illustrated in the accompanying drawings, in which:—

Fig. 1 is a longitudinal sectional view of a 0 pipe constructed in accordance with the invention.

Fig. 2 is a section on line 2—2 of Fig. 1.

Fig. 3 is a perspective view of the tobacco receptacle.

Fig. 4 is a perspective view of the smoke 5 duct and condensate chamber.

The improved pipe includes a bowl 1 and a stem portion 2 integral therewith, such parts aside from the details hereinafter noted being of any shape, size, or material. A mouth piece 3 is arranged for removable con-

nection with the stem 2, the connection being preferably a slip joint, though obviously any type of connection may be employed.

A condensate chamber 4 is secured in the bottom of the bowl 1, preferably through the medium of a screw 5 through the bottom of the bowl and accessible from the exterior, to permit separation of the chamber when desired. The chamber is preferably of thin metal of high heat conductivity, as, for example, aluminum, and has a diameter somewhat less than the interior diameter of the bowl, as seen in Fig. 1. The bottom of the condensate chamber is of more or less conical form to permit free circulation of air beneath such chamber for cooling purposes.

A smoke duct 6, preferably of metal of high heat conductivity and of comparatively small bore and diameter, is removably secured, preferably by threaded connection 7 in the wall of the condensate chamber, the arrangement providing an open communication between the smoke duct and chamber. The smoke duct 6 extends lengthwise the stem 2 and mouth piece 3, terminating short of the free end of the latter. The exterior diameter of the smoke duct is materially less than the interior diameter of the stem and mouth piece, to thereby provide a free and uninterrupted space surrounding the smoke duct, for a purpose which will be later explained.

The free end of the smoke duct enters a reduced portion of the mouth piece, indicated at 8, the free end of the duct being thus sealed against the mouth piece and stem in advance of the free end of the duct. Of course the duct and mouth piece may be otherwise formed to maintain the desired seal.

A tobacco receptacle 9 is designed to be more or less snugly seated within the bowl 1. The receptacle seats at its lower end in the upper open end of the condensate chamber 4, the upper edge of the latter being formed to provide a seat for the receptacle, as indicated in Fig. 1. The receptacle is open at the upper end, and is formed in its otherwise closed bottom with a series of openings 10, three such being illustrated, whereby 100

free communication is established between the tobacco receptacle 9 and the condensate chamber 4. The receptacle is fitted to the bowl, and the latter is formed on its inner surface preferably diametrically opposite the stem, with a vertically extending channel 11, through which air is freely admitted to the top of the tobacco receptacle. The fit of the receptacle may be such as to permit air to rise freely all around it, but if it is to be fitted snugly, the upper edge of the receptacle may be formed with a notch 12, to be aligned with the channel 11, for free air admission to the top of the receptacle.

15 The mouth piece, in advance of the sealing junction of the smoke duct therewith, is formed with one or more openings 13, establishing free air inlet to the stem and mouth piece externally of the smoke duct, these 20 openings 13 forming the sole air admissions to the pipe.

25 The bowl, and thereby the tobacco receptacle is closed by a removable cover 14, fitting the upper edge of the bowl in sealing relation, as indicated in Fig. 1.

30 The tobacco being placed in the tobacco receptacle 9 and lighted, suction on the mouth piece in the usual manner causes air to enter the openings 13, pass lengthwise the mouth piece and stem, entirely surrounding the smoke duct, pass into the bowl, completely enveloping the condensate chamber 4, and rise through the channel 11. The air then passes downwardly through the tobacco in 35 the receptacle 9, the smoke and air passing into the condensate receptacle or chamber 4, through the openings 10 in the tobacco receptacle 9, and from the condensate chamber through the smoke duct 8.

40 The smoke duct and condensate chamber are both open to the influence of the incoming cool air. As both are preferably of comparatively thin metal of high heat conductivity, the cooling effect of the incoming air 45 is pronounced, and the smoke reaching the mouth of the user is cool and dry. The cooling effect on the condensate chamber insures a more or less complete condensation of any liquid contained in the smoke.

50 By providing a plurality of holes in the tobacco receptacle and having a comparatively large air inlet, little effort is required on the part of the user in drawing on the pipe. As no particles of tobacco can enter 55 the smoke duct, the pipe is essentially non-clogging, nor can any liquid enter the mouth. The provision of the sealing cap permits use of the pipe in high winds, and prevents distribution of lighted particles of tobacco. All 60 parts are readily removable and replaceable, thus contributing to the convenience of keeping the pipe in perfect order and operation. Any part can be removed and replaced by a new part, and particularly the tobacco receptacle, the part subjected to greatest wear

through the burning tobacco, can be conveniently removed for cleaning or renewal. Of course, the tobacco receptacle which is the only part in contact with the tobacco, may be separately made of high grade material of particular function in connection with burning tobacco, while the remaining parts of the pipe proper, that is the stem and bowl, may be constructed of inferior material, thus giving the advantage of a high grade pipe of 75 comparatively little cost.

Having thus described the invention, what is claimed as new, is:—

1. A tobacco pipe including a bowl, a stem, a tobacco receptacle loosely placed in the bowl, a condensate chamber removably secured in the bowl and in open communication with the tobacco receptacle, a smoke duct leading from the condensate chamber and extending lengthwise the stem, and means for admitting air through the stem remote from the bowl.

2. A tobacco pipe including a bowl, a stem, a condensate chamber removably secured in the bottom of the bowl, a smoke duct in open communication with said chamber and extending through the stem, the bottom of the chamber being conical, a tobacco receptacle removably seated on the chamber and formed in its bottom with an opening to establish communication with the chamber, the stem being formed with air inlet openings remote from the bowl and stem juncture.

3. A tobacco pipe having a smoke channel leading through a condensate chamber to the tobacco, said pipe having an air inlet located to compel the entering air to travel throughout the length of the smoke duct and envelop the condensate chamber.

4. A tobacco pipe including a bowl, a stem, a condensate chamber removably secured in the bottom of the bowl and otherwise free of contact with the bowl, a tobacco receptacle fitted within the open upper end of the condensate chamber and having restricted communication with such chamber, and a smoke duct leading from the condensate chamber and through the stem, the stem being formed with air-inlet openings to admit air through the stem to and around the condensate chamber.

5. A tobacco pipe including a bowl, a stem leading therefrom, a condensate chamber removably secured centrally of the bottom of the bowl, said chamber being free of contact with the bowl beyond such connection, a tobacco receptacle having a closed bottom except for a single opening and fitted within the open upper end of the condensate chamber, a smoke duct having threaded connection with the condensate chamber, said smoke duct extending through the stem and being of less diameter than the interior of the stem, a mouth piece for the stem, said mouth piece having sealing cooperation with the exterior

of the smoke duct near the free end of the latter, the stem being formed with air-inlet openings to admit air to the interior of the stem surrounding the smoke duct, and a removable cap for the bowl serving to cover the bowl and tobacco receptacle.

5 In testimony whereof I affix my signature.
GEORGE A. MILKIE. [L. s.]
